UNITED STATES PATENT OFFICE.

MADELINE B. HOUSTON, OF EVANSTON, ILLINOIS.

ENVELOPE SHIELD FOR CRIB BEDS.

Application filed November 27, 1925. Serial No. 71,566.

My invention relates to envelope shields for crib beds, and the object of the invention is to provide an inexpensive and portable device of this character adapted for applying 5 to a crib and thereby protect a child occupying the crib bed from drafts and currents of air.

A further object of the invention is to provide an envelope shield having facilities 10 for applying the same to cribs having facilities for suspending the bed therein at various levels.

A further object of the invention is to provide the envelope shield with overhanging 15 flaps having pockets for carrying articles essentially necessary for the comfort of a child occupying the bed.

I attain these objects and other advantages by the parts and structure illustrated in the 20 accompanying drawing in which—

Figure 1 is a perspective view of an open child's crib and to which the invention is applied, parts of the customary screen filling being omitted.

Figure 2 is a view of the foot end of the 25 crib, and showing the overlapping portions of the side flaps, the screen panels being omitted.

Figure 3 is a longitudinal section of the 30 crib with shield, and showing the child's bed suspended in the crib, the screen panels being omitted.

Figure 4 is a detail of one corner of the 35 bag portion of the shield, and showing the holes therein provided for the passage of the means for fastening the bed to the crib frame and—

Figure 5 is a corner member of the crib 40 frame and showing the hooks thereon for suspending the bed in the crib.

Similar numerals of reference refer to corresponding parts throughout the several views.

The numeral 1 designates an open type 45 child's crib provided with the customary screen filling 2. The envelope shield 3 is made of any suitable flexible material, preferably of woven cotton, wool, or silk goods, and sewed and formed to shape to conform 50 to the shape and form of the crib. The shield consists of a rectangular bag portion 4 adapted to hang loosely into the crib, so that the ends and sides of the bag will be disposed in close relation to the inner sides 55 and ends of the crib. On the upper edges of the bag portion are sewed end flaps or

aprons 5 and side flaps or aprons 6, both of which are adapted to overhang the ends and sides of the crib and lie in close relation thereto. The side flaps 6 are a little longer 60 than the length of the crib to provide overlapping end portions 7 to overlap the end portions of the end flaps at the corners of the crib. The portions 7 are provided with a plurality of buttons 8 having facility for 65 receiving snaps 9 fastened on the end margins of the end flaps. A lapped seam 10 is provided and sewed on the upper edges of the bag and the edges of the side and end flaps, said lapped seam being adapted to 70 bear on the upper edges of the top members of the frame of the crib. In the corners of the bag are apertured holes 11 provided with eyelets 12, and which holes are adapted for the passage therethrough of bed suspending members 13 and which are mounted at the corners of the bed 14. The members 13 are connected to hooks 15 which are mounted in the angles of the corner pieces 16 of the crib frame, as 75 shown in Figure 5. A flap 17 may be sewed on the upper edge of the shield at the foot end of the crib to serve as a partial cover for the mouth of the bag. On the outer sides of the end and side flaps or aprons are pockets 80 provided with fastening devices 19 to hold them closed and which pockets are adapted to receive articles of clothing and things necessary for the comfort of a child 85 occupying the crib.

The envelope shield is applied to the crib by first removing therefrom the crib bed and then placing the bag portion of the shield into the crib with the flaps 5 and 6 overhanging the ends and sides of the same, thus bringing the strip 10 to bear on the upper rails of the crib frame. Then the overlapping portions 7 are placed over the end flaps and secured thereto by means of the buttons 8 engaging the snaps 9. The crib bed is then suspended in the crib and inside the bag portion 4 of the shield at any desired level by passing the members 13 through the holes 11 in the corners of the bag and connecting the same to the hooks 15, on the corner pieces 16 of the frame of the crib. In the pockets 18 may be stored articles used with the crib. When the shield is not used for the protection of the child in the crib, the same may be packed and stored in a compact and convenient package. The shield may be made of figured goods,

in which case it is both ornamental and useful.

Having described my invention what I claim is—

- 5 1. In an envelope shield for crib beds, the combination with a crib frame, of a box shaped bag made of suitable flexible material disposed within the crib and having its walls in close relation to the inner sides
10 of the crib, a flexible strip united with the upper edges of said bag and adapted to lie upon the upper edges of the crib frame, individual flexible flaps united with said strip and depending therefrom and partially covering the outer sides and ends of the crib, the side flaps being extended lengthwise to provide overlapping end portions adapted to overlap the end flaps, and fastening devices mounted on the end flaps and the overlapping portions of the side flaps adapted to hold the shield in close relation to the crib.
- 15 2. In an envelope shield for crib beds, the combination with a crib having a bed, of a box shaped bag made of suitable flexible material disposed within the crib and having its walls in close relation to the inner sides of the crib, a flexible strip united with the upper edges of the bag and adapted to lie upon the upper edges of the crib frame, individual flexible flaps united with said strip and depending therefrom and partially covering the outer sides and ends of the crib, the side flaps being extended lengthwise to provide overlapping end portions adapted to overlap the end flaps, fastening devices mounted on the end flaps and the overlapping portions of the side flaps adapted to hold the shield in close relation to the crib, a plurality of holes apertured in the corners of the bag for the passage of bed suspender members to a connection with the corners of the crib frame.
- 20 3. In an envelope shield for crib beds, the combination with the crib having a bed, of a box shaped bag made of suitable flexible material disposed within the crib and having its walls in close relation to the inner sides of the crib, a flexible strip united with the upper edges of the bag and adapted to lie upon the upper edges of the crib frame, individual flexible flaps united with said strip and depending therefrom and partially covering the outer sides and ends of the crib, the side flaps being extended lengthwise to provide overlapping end portions adapted to overlap the end flaps, fastening devices mounted on the end flaps and the overlapping portions of the side flaps adapted to hold the shield in close relation to the crib, a plurality of holes apertured in the corners of the bag for the passage of bed suspender members to a connection with the corners of the crib frame, and a flap united with the foot end of the shield and adapted to cover a part of the mouth of the bag.

MADELINE B. HOUSTON.
